UNITED STATES PATENT OFFICE

ANNA C. LONGFELLOW, OF LARCHMONT, NEW YORK

NEEDLE THREADER

Application filed February 27, 1929. Serial No. 343,086.

The present invention relates to improvements in sewing devices or appliances, and more particularly it pertains to a device for facilitating the threading of needles.

5 It is one object of the present invention to provide a novel needle threading device by which a plurality of needles may be threaded at a single operation.

10 A feature of the present invention consists in the provision of means for holding a plurality of needles in such a manner that the eyes of the several needles will occupy a position in direct alinement with one another.

15 Another feature of the present invention is so to construct the device that after the needles have all been threaded, they may be singly removed together with a length of thread without disturbing the needles not removed and without disturbing the thread 20 with which they are threaded.

Other features of the invention relate to certain novel and improved constructions, arrangements and combinations of parts herein-after described and particularly pointed out 25 in the claims, the advantages of which will be readily understood and appreciated by those skilled in the art.

The invention will be clearly understood 30 from the accompanying drawing illustrating the invention in a preferred form, and the following detailed description of the construction therein shown.

In the drawing—

35 Figure 1 is a view in elevation, partly in section of a needle threading device constructed in accordance with the present invention;

Figure 2 is a vertical sectional view thereof taken on the line 2—2 of Figure 1;

40 Figure 3 is a horizontal sectional view thereof taken on the line 3—3 of Figure 1; and

Figure 4 is a detail sectional view taken on the line 4—4 of Figure 1.

45 In the accompanying drawing, the reference numeral 5 designates a base which may be formed of any material suitable for the purpose, and as more clearly shown in Figure 3, the base 5 is preferably of elongated form 50 and has a lateral extension 6.

The needles are designated by the numeral 10, and are supported upon their pointed ends upon the base 5 and to accomplish this result a needle holding member 7 is provided. This needle holding member 7 preferably 55 comprises a base portion 8 and a vertically-extending portion 9. The vertically-extending portion 9 is provided with a needle receiving slot or passage 11 which extends through the upper face thereof as shown in Figure 3. 60 The member 7 may be formed from any suitable material so long as it is possessed of sufficient rigidity to maintain the needles in vertical position.

In connection with the needle holding means, separate means is provided to maintain the needles in such position that their eyes will at all times be in alinement with one another. In one embodiment of the invention, this last mentioned means consists 65 of two resilient plates 12 secured in any desired manner as by rivets to the sides of the vertically-extending portion 9 of the needle holding member 7 as shown in Figure 2 of the drawing. These resilient plates 12 are 70 opposed with relation to each other, and are so shaped that the space between them forms a needle passage, the width of which is slightly less than the thickness or diameter of the needles which are to be held therein, thus 75 providing, when the needles are placed in the holder 7, resilient means for clamping and properly positioning the needles with the eyes thereof in alinement with one another.

To further insure that the several needles will be retained in position with their eyes in alinement, the needles may be provided at that point at which they are engaged by the plates 12 with slightly flattened portions 15, which are not, however, of sufficient dimension as to interfere with the sewing operation of the needles. If these flattened portions 15 be arranged diametrically opposite each other on each needle and in a plane at right angles to the axis of the eye of the needle, it will be obvious that when the needles are positioned in the holder 7, with their flattened portions engaged by the members 12, the needles will occupy such positions that the eyes thereof 100 will be in alinement with each other.

Means is provided for guiding or directing a thread through the alined eyes of several needles mounted in the holder 9 and in the present embodiment of the invention this 5 means is shown as constituting a separate element in the form of a block 16 removably engageable with the eye ends of the several needles. This block is shown as cylindrical in form, but it will be understood that it is 10 not necessarily limited to this form and may be constructed in various other forms without departing from the present invention.

This block 16 is provided with a needle receiving passage 17 and leading through each 15 end of the block 16 and into the needle passage 17 thereof there is a tapered passage. These tapered passages are designated by the reference numerals 18 and 19. Extending radially of the tapered passage 18, there is a 20 slot or passage 20, which extends entirely through the wall of the block 16. The tapered passage 19 may also be provided with such a passage, but as will be hereinafter explained such a slot or passage in the wall of 25 the tapered passage 19 is not necessary to the successful operation of the device.

The extension 6 of the base 5 carries a standard or the like 22, which serves as a mount for a spool of sewing thread, as shown 30 in Figure 1, the spool being designated by the numeral 21.

In use, a plurality of needles are placed in the needle receiving slot 11 of the needle holder, with their point ends downward, and in 35 such position that the eyes of the several needles will be in alinement with each other in which position they will be retained by reason of engagement of the resilient members 12 with the slightly flattened portions 15 thereof. After the needles have been positioned as above described, the block 16 is positioned over the eye ends of the several needles, the needles being received in the slot 17 of said block. When the block 16 has been 45 placed in the position described the axis of the openings 18 and 19 will be in alinement with the axis of the eyes of the alined needles. If now a thread be passed into the tapered opening 18 of the block 16, it will, by the tapered wall of said opening 18, be directed into 50 the eye of the first needle to the right in Figure 1 and may be passed through the eyes of all of the needles and through the tapered opening 19. The block 16 may now be removed simply by lifting the same off from the upper ends of the needles during which operation the thread is free to pass through the radial passage 20 in the wall of the tapered opening 18, the free end of the thread being 55 drawn through the tapered opening 19.

Removal of the block 16 leaves the plurality of needles held securely in the holder 7 by the resilient plates 12, with a single length of thread passing through the eyes of all the 60 needles. After thread of the desired length

for one sewing operation has been drawn through the eyes of the several needles, the first needle at the left in Figure 1 may be removed and the thread severed, leaving the remaining needles in place in the holder with 70 a single length of thread passing through the eyes thereof. The operation of removing the first needle to the left of Figure 1 may be repeated in lieu of re-threading a single needle, as is the general custom, each time a new thread is desired. After all of the 75 needles have been removed and used, they may be replaced, and again be threaded in the above described manner.

From the foregoing description, it will be 80 apparent that the present invention provides a novel means for simultaneously threading a plurality of needles, and retaining them in their threaded condition until used, thus materially saving time over re-threading a single 85 needle each time a length of sewing thread has been consumed.

While the invention has been illustrated in its preferred form it is to be understood that it is not to be limited to the form shown and that it may be practiced in such other forms as rightfully fall within the purview of the 90 appended claims.

What is claimed as new is:

1. In a needle threading device, a base 95 member for supporting a plurality of needles upon their point ends, means embracing said needles for positioning the needles with their eyes in alinement, and means for guiding a thread through the alined eyes of said needles, 100 said last mentioned means comprising a member having a slot for receiving the eye ends of said needles, and a tapered opening leading through one of its walls to said slot.

2. In a needle threading device, a base member 105 for supporting a plurality of needles upon their point ends, clamping means for engaging said needles and holding them in position with their eyes in alinement, and means for removably engaging the free ends of the 110 needles carried by the support, for guiding a thread through the eyes of said needles, said last mentioned means comprising a block having a needle receiving passage therein, and a tapered thread guiding opening passing 115 through one of the end walls of said block and leading into the needle receiving passage thereof.

3. A needle threader comprising means engaging the sides of a plurality of needles adapted to hold them with their sides touching, means engaging the ends of said needles to position them in said first named means with their eyes in alignment, a spring pressed clamp adapted to engage flattened portions 120 of the needles and thereby to hold them with their eyes coaxial, and a funnel shaped guide adapted to guide a thread to and along the common axis of said eyes.

4. A needle threader comprising means en- 125

gaging the sides of a plurality of needles having flattened side portions, said means being adapted to hold them with their sides touching, means engaging the ends of said needles to position them in said first named means with their eyes in alignment, a clamp adapted to engage the flattened portions of the needles and thereby to hold them with their eyes coaxial, and a funnel shaped guide adapted to guide a thread to and along the common axis of said eyes.

Signed at New York, N. Y., this 21st day of February, 1929.

ANNA C. LONGFELLOW.
